MICROWAVE ENERGY AMPLIFIER

Winston M. Gottschalk, Watertown, Mass., assignor to Raytheon Manufacturing Company, Newton, Mass., a corporation of Delaware

Application October 18, 1949, Serial No. 122,098

5 Claims. (Cl. 315—4)

1

This invention relates to amplifying devices, and, more particularly, to amplifying devices for electrical energy in the microwave region of the electromagnetic spectrum.

It is among the objects of the present invention to provide a device of the general character specified which is relatively simple in construction and which is relatively easy and economical to fabricate and assemble.

It is a further object of the present invention to provide an amplifying device for microwave energy which is reasonably frequency-insensitive up to a frequency of about 10,000 megacycles per second.

It is a still further object of the present invention to provide a device which, while capable of giving only relatively low microwave energy amplification, for example, amplification by a factor of about 5, nevertheless is efficient.

These, and other objects of the present invention, which will become more apparent as the detailed description progresses, are attained, in general, in the following manner.

The device contemplates the provision of an evacuated envelope containing means for projecting an electron beam along a predetermined path. Disposed adjacent this path is a means, receptive of the microwave energy to be amplified, for deflecting the electron beam from said predetermined path in synchronism with the alternations of said energy, said beam being thereby caused to move along additional paths which are angularly displaced with respect to said predetermined path. Another means is disposed adjacent said additional paths, in longitudinally spaced relationship with respect to said deflecting means, for absorbing energy from the electron beam as it passes thereby. The amount of energy necessary to deflect the electron beam at the first above-mentioned means is relatively small, but the electron beam itself, which is locally generated and which is of substantial density, constitutes a relatively large current flow. Hence, as this beam moves past the second above-mentioned means, substantial energy is extracted therefrom which represents an amplification of the deflecting input energy.

In the accompanying specification there shall be described, and in the annexed drawing shown, an illustrative embodiment of the amplifying de-

2

vice of the present invention. It is, however, to be clearly understood that the present invention is not to be limited to the exact details herein shown and described for purposes of illustration only, inasmuch as changes therein may be made without the exercise of invention and within the true spirit and scope of the claims hereto appended.

In said drawing:

10 Fig. 1 is a more or less schematic representation of an amplifier made in accordance with the present invention; and
15 Fig. 2 is a similar view of the same, in perspective to more clearly show the physical and electrical relationships between the components thereof.

Referring now more in detail to the aforesaid illustrative embodiment of the present invention, with particular reference to the drawing illustrating the same, the numeral 10 designates an evacuated envelope at one end of which there is mounted an electron gun 11 of substantially conventional construction, and at the other end of which there is mounted a collecting electrode 12. The gun includes a cathode 13, preferably, of the indirectly-heated type, for supplying, upon suitable heating by a voltage source 14, a copious flow of electrons, and appropriate electron focusing and accelerating electrodes 15. The cathode 13 and collecting electrode 12 are adapted to have a voltage applied therebetween, for example, by means of a voltage source 16, whereby an electron beam is projected between said electrodes along a first path A which lies, for example, along the longitudinal axis of the envelope 10.

Spaced from the electron gun 11, along the path A, is a means, here shown as a lecher-wire system 17 straddling the path A, which, when excited by the microwave energy to be amplified, for example, from a two-wire line 17' which may be sealed through the envelope 10 and connected to said lecher-wire system, deflects the electron beam, for example, above and below the path A in synchronism with the alternations of said energy, so as to cause said electron beam to be projected alternately along paths B and C. While a lecher-wire system has been specifically shown, it is to be understood that other appropriate wave guiding means may be employed instead.

Preferably, the lecher-wire system is shorted at one end, as at 18, and the region in which the electron beam passes between the wires of said lecher-wire system is a quarter wave length from said shorted end, whereby said electron beam is in the region of maximum voltage along the standing wave set up on the lecher-wire system.

Spaced from the collecting electrode 12, along the paths B and C, is a pair of two-wire lines 19 and 20, said lines being connected by another two-wire line 21 to straddle the three paths A, B and C. Here, again, other appropriate wave guiding devices may be employed in place of the two-wire lines shown and described. The distances along the lines 19 and 20 from the points where said lines are adjacent the paths B and C to the points of connection of said lines to the line 21 are, preferably, a half wave length, and the length of the line 21 is also, preferably, a half wave length, the total distance from the point where the path B passes the line 19, through the line 21, to the point where the path C passes the line 20, preferably, always being an odd number of half wave lengths. The line 20 is shorted, as at 22, at a point a quarter wave length from the path C, and the free end of the line 19 may be connected to a suitable load for example, by means of a two-wire line 19' which may be connected to the ends of said line 19 and sealed through the envelope 10.

In operation, the positive potential applied to the collecting electrode 12 causes the electron beam from the gun 11 to move along the path A centrally between the wires of the lecher-wire system 17 and centrally between the two-wire lines 19 and 20. When the microwave energy to be amplified is applied to the lecher-wire system 17, the electron beam is deflected from the path A in synchronism with the alternations of the input so as to be alternately projected along the paths B and C. As the beam passes the line 19, it induces a voltage between the wires of said line, thus setting up a current therein. By the time the resulting wave reaches a point along the line 20 adjacent the path C, the electron beam, due to a reversal of the polarity of the input to the lecher-wire system 17, is moving along said path C to induce a voltage between the wires of the line 20 which is in phase with the first above-mentioned voltage. This is due, of course, to the odd number of half wave lengths between the paths B and C along the lines 19, 20 and 21.

Inasmuch as the electron beam between the gun 11 and electrode 12 represents a heavy current, the energy absorbed by the lines 19 and 20 represents an amplification of the input to the lecher-wire system 17.

This completes the description of the aforesaid illustrative embodiment of the present invention. It will be noted from all of the foregoing that the amplifier of the present invention is simple in construction, easy and economical to fabricate and assemble, and provides efficient amplification, by a factor of about 5, of microwave energy of up to about 10,000 megacycles per second.

Other objects and advantages of the present invention will readily occur to those skilled in the art to which the same relates.

What is claimed is:

1. A microwave energy amplifier comprising: an evacuated envelope containing means for projecting a beam of electrons along a first path; means, mounted in said envelope adjacent said first path and receptive of the microwave energy

to be amplified, for deflecting said beam of electrons from said first path, whereby the same is projected alternately along additional paths which are angularly displaced from and lie on opposite sides of said first path; and a pair of resonant two-wire lines, mounted in said envelope, respectively, adjacent said additional paths, in longitudinally spaced relationship with respect to said last-named means, for inductively absorbing energy from said beam of electrons; each of said two-wire lines including a pair of conductors lying side by side along the length of said envelope.

2. A microwave energy amplifier comprising: an evacuated envelope containing means for projecting a beam of electrons along a first path; a lecher-wire system, mounted in said envelope straddling said first path and receptive of the microwave energy to be amplified, for electrostatically deflecting said beam of electrons from said first path, whereby the same is projected alternately along additional paths which are angularly displaced from and lie on opposite sides of said first path; and a pair of two-wire lines, mounted in said envelope, respectively, adjacent said additional paths, in longitudinally spaced relationship with respect to said lecher-wire system, for inductively absorbing energy from said beam of electrons.

3. A microwave energy amplifier comprising: an evacuated envelope containing means for projecting a beam of electrons along a first path; means, mounted in said envelope adjacent said first path and receptive of the microwave energy to be amplified, for deflecting said beam of electrons from said first path, whereby the same is projected alternately along additional paths which are angularly displaced from and lie on opposite sides of said first path; and a pair of two-wire lines, mounted in said envelope, respectively, adjacent said additional paths, in longitudinally spaced relationship with respect to said last-named means, for inductively absorbing energy from said beam of electrons; said two-wire lines being connected by a third line which is of an electrical length equal approximately to an odd number of half wave lengths of said microwave energy, whereby said two-wire lines absorb energy of similar phase.

4. A microwave energy amplifier comprising: an evacuated envelope containing means for projecting a beam of electrons along a first path; a lecher-wire system, mounted in said envelope straddling said first path and receptive of the microwave energy to be amplified, for electrostatically deflecting said beam of electrons from said first path, whereby the same is projected alternately along additional paths which are angularly displaced from and lie on opposite sides of said first path; and a pair of two-wire lines, mounted in said envelope, respectively, adjacent said additional paths, in longitudinally spaced relationship with respect to said lecher-wire system, for inductively absorbing energy from said beam of electrons; said two-wire lines being connected by a third line which is of an electrical length equal approximately to an odd number of half wave lengths of said microwave energy, whereby said two-wire lines absorb energy of similar phase.

5. A microwave energy amplifier comprising: an evacuated envelope containing means for projecting a beam of electrons along a first path; means, mounted in said envelope adjacent said first path and receptive of the microwave energy

to be amplified, for deflecting said beam of electrons from said first path, whereby the same is projected along a second path which is angularly displaced from said first path; and a resonant structure, mounted in said envelope, adjacent said second path, in longitudinally spaced relationship with respect to said last-named means, for inductively absorbing energy from said beam of electrons; said resonant structure including a pair of conductors lying side by side 10 along the length of said envelope.
